UNITED STATES PATENT OFFICE.

EARL S. GIBSON, OF RIDGEWOOD, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed May 22, 1923. Serial No. 640,648.

To all whom it may concern:

Be it known that I, EARL S. GIBSON, a citizen of the United States, residing at 43 Garfield Place, Ridgewood, in the county of Bergen, State of New Jersey, have invented certain new and useful Improvements in Telephone-Exchange Systems, of which the following is a full, clear, concise, and exact description.

10 This invention relates to telephone exchange systems and especially to systems employing automatic switching apparatus for setting up connections.

15 The object of the invention is to provide, in systems where designations are recorded on controlling equipment, improved means for transferring such records from one part of the system to another.

20 A feature of the present invention relates to the provision of an impulse sending device consisting of relays for creating and sending code impulses representing recorded designations from one point to another.

25 Other features contemplated by this invention will be more thoroughly understood from a consideration of the following detail description and also from the appended claims.

30 In the drawings Figs. 1 to 9, when arranged in the order illustrated in the diagram of Fig. 10, disclose so much of a telephone exchange system incorporating the features of the invention as is necessary to a thorough understanding thereof.

35 Fig. 1 illustrates in schematic manner a calling subscriber's line and a line switch of the coordinate type for extending the lines to outgoing trunks. This figure also shows diagrammatically a sender selector switch of the coordinate type.

40 Fig. 2 shows a portion of the detailed circuits of one of the trunks outgoing from the line switch in Fig. 1 and also a diagram of a coordinate group selector switch in which said trunk terminates.

45 Figs. 3, 4, 5 and 6 taken together show one of a number of register sender controlling mechanisms which are associable with the trunks by means of the sender selector switch illustrated in Fig. 1.

50 Fig. 3 illustrates the counting relays and other control relays of the sender. Fig. 4 shows the controlling relays and circuits for sending code impulses representing recorded designations. Figs. 5 and 6 show

four relay registers on which designations are recorded under the control of the calling subscriber's line.

Fig. 7 illustrates the incoming end of an inter-office trunk circuit. This trunk appears in a cord circuit at a manual operator's position in the called office. This figure also shows a called subscriber's line terminating in the manual office.

Figs. 8 and 9 show a register circuit serving the purpose of a call indicator.

The line switch 100, the group selector switch 200 and the sender selector switch 110 are of the coordinate type such as shown and described in detail in the application of S. B. Williams, Serial No. 596,179, filed Oct. 23, 1922, issued as Patent No. 1,517,331, Dec. 2, 1924.

The calling subscriber on initiating a call has his line automatically extended by way of the line switch 100 to an idle trunk such as the trunk 103 terminating in the group selector or district selector switch 200. At the same time the trunk 103 is associated with an idle register sender by means of the sender selector switch 110. Following this the subscriber dials a number of digits which are recorded on the several registers of the associated sender. Thereafter in any suitable manner the register sender determines the selective operation of the district selector switch 200 and an idle trunk is selected leading to the distant manual office in which appears the wanted line.

Inasmuch as the present invention is not concerned with the detailed operation of the selector switches nor with the manner in which the register sender exercises its control over the switches, several elements have been illustrated in schematic fashion. For a more detailed explanation of the way in which the operating circuits of the various switches function and the manner in which the register senders control the selection of trunks, reference is made to the above mentioned patent to Williams.

After a trunk has been selected by the switch 200 in the mechanical office leading to the distant manual office illustrated in Figs. 7, 8 and 9, it is next necessary to transfer the record established on the register sender over the trunk to the distant office to bring about the operation of the call indicator in order that the operator may be advised of the called line number. This is

accomplished by means of the equipment shown in Fig. 4 wherein the relay device 407 and 408 creates impulses which form codes according to the record established on the registers and transmits these impulses over the line to the distant manual office. The record is established in the distant manual office on the call indicator registers and causes the illumination of lamps before the operator. In case the distant called office is one involving machine switching apparatus for building a connection, code impulses would be transferred to a register sender, which in turn, would control switches in the called office.

A detail description will now be given of the establishment of a connection between a calling line in the mechanical office such as line 101 and a called subscriber's line 719 in a distant office involving the transfer of the record from the first office to the second office. Assume that the numerical part of the designation of the wanted line is 2 5 3 1. The four digits of the numerical designation are recorded on the four numerical registers of the sender shown in Figs. 5 and 6. Since the call involves the extension of a connection to a distant office, it may be desirable in some cases to employ office designations for controlling the selective switches in the first office to select trunks leading to the desired distant office. Where office designations are involved the register sender will have other registers similar to those shown for recording these designations and for controlling the local switches accordingly.

When the calling subscriber initiates the call his line 101 is extended automatically through the line switch 100 to the first idle one of a number of outgoing trunks 102, 103, etc. If the trunk 103 is the first one to be idle, it is selected and the calling line is extended thereover to the district selector switch 200. At the same time that the calling line is extended to the district selector the sender selector switch 110 is operated automatically and the trunk 103 is connected to the idle register sender shown in the drawing.

During the operation of the sender selector switch 110 a circuit may be closed in any suitable manner for the relay 204. Relay 204 operates and applies ground potential to the holding or sleeve conductor 111. As soon as the sender selector switch 110 is operated, it may complete a circuit in any suitable manner for the relay 203. Relay 203 closes a substitute circuit for the slow releasing relay 204. Relay 203 also extends the tip and ring conductors of the trunk through the sender selector switch 110 to the selected sender. An impulse circuit is now traceable from battery through the right-hand winding of relay 300 in the

sender, contact of relay 301, conductor 318, inner left contact of relay 311, thence through the selector 110, conductor 220, inner lower contact of relay 203, conductor 105, through the line switch 100, over the loop of the calling line and returning through the line switch 100 to the conductor 104, inner upper contact of relay 203, conductor 221, through the switch 110, outer left contact of relay 311, conductor 319, contact of relay 301, upper winding of coil 302 to ground. Relay 300 closes a circuit for slow release relay 304, which in turn, closes a circuit for relay 310. Relay 310 applies holding ground to the conductor 320 which results in holding circuits for the sender selector switch 110 and for the relay 203 in the trunk circuit. Relay 304 completes a circuit from battery through the coil 303, left-hand winding of relay 305, contact of relay 304 to ground. Relay 305, however, does not operate since its left winding is shunted by a circuit from battery through the coil 303, right contact of relay 300 directly to ground at the contact of relay 304. The apparatus is now in condition for receiving the first series of impulses.

The calling subscriber, therefore, manipulates his impulse transmitter to send a series of two impulses representing the first numerical digit. In response to the first opening of the line, relay 300 releases and opens the shunt around the left winding of relay 305 and this latter relay operates. Relay 305 closes a circuit from battery through its right winding and inner right contact, outer left contact of relay 306, conductor 321 to ground at the outer left contact of relay 310. Relay 305 also closes a circuit from battery through the winding of slow to release relay 308, outer right contact of relay 305 to the grounded conductor 321. Moreover, relay 305 closes a circuit through the right-hand winding of relay 306. Relay 305 also closes a circuit from battery through the winding of relay 307, outer left contact of relay 305 to the grounded conductor 321. Relay 307 locks through its inner left contact, right contact of relay 309 to the grounded conductor 321. Relay 306 operates and closes a circuit from battery through its left-hand winding and inner left contact to the grounded conductor 321. Relay 306, in addition, completes a circuit from battery through its right winding and right contact, conductor 322, outer right back contacts of relays 315, 314, 313 and 312, winding of relay 312, outer left back contact of relay 313, conductor 323, outer left contact of relay 309, left front contact of relay 307, right contact of relay 309 to the grounded conductor 321. Relay 312, however, does not operate in the above traced circuit due to the shunt main-

tained by the relay 305 so long as the line circuit is open. When the line circuit is closed following the first opening, relay 300 operates again and replaces the shunt 5 around the left winding of relay 305 and relay 305 immediately releases. Relay 305 removes the shunt from around the winding of relay 312 and this relay attracts its armatures.

10 It should be noted at this point that the armatures of the counting relay 312, which is also true of the remaining counting relays 313, 314, 315 and 316, are so arranged that the inner right contact is closed slightly 15 in advance of the opening of the outer right back contacts. By this arrangement a locking of the counting relay is certain to take place before the energizing circuit is opened. Immediately that the relay 312 opens its 20 right back contact the circuit through the right winding of relay 306 is opened. Relay 306 is wound differentially. While the flux set up by the left-hand winding of this relay is not sufficient to overcome the flux set up 25 by the right-hand winding to cause a release during the time the circuit of the right-hand winding is closed, when the circuit of the right-hand winding is opened, the effect of the differential action between the two 30 windings is a quick release of the armatures. Relay 312, in operating, locks in a circuit from battery through its inner right contact and winding, outer left back contact of relay 313 to ground over conductor 323.

35 In response to the next opening of the line for the second impulse of the series, relay 300 releases, relay 305 operates and relay 306 closes a circuit by way of conductor 322, through the outer right back contact of relays 313 and 314, outer right front contact 40 of relay 312, winding of relay 313 outer left back contact of relay 314, conductor 323, outer left contact of relay 309, left front contact of relay 307, right contact of relay 309 to the grounded conductor 321. Counting relay 313 operates and in the manner 45 above described locks through its inner right contact and the outer left back contact of relay 314 to the grounded conductor 323. Relay 313, in operating, opens the holding circuit of relay 312 and this latter relay 50 releases.

55 After the usual interval has elapsed following the impulse series, slow-to-release relay 308 becomes deenergized. It will be noted that this relay has its circuit momentarily interrupted by the relay 305 during the sending of pulses, but does not release by reason of its slow operating characteristic. A circuit is now closed from ground over conductor 321, through the contact of relay 308, right contact of relay 307, inner left contact of relay 309, conductor 324 right back contact of relay 507, winding of relay 508 to battery. Relay 508 operates and con-

nects the control leads from the counting relays to the relays of the register 500. Relay 508 closes a circuit from battery through its winding and inner upper contact, thence over conductor 517, winding of relay 309, right contact of relay 307, contact of relay 308 to the grounded conductor 321. Relay 309, however, being shunted by the above traced circuit does not operate at this time.

75 With relay 508 operated a circuit is closed from ground over conductor 323, outer left front contact of relay 313, conductor 325, contact of relay 508, winding of relay 504, winding of relay 502 to battery. Relays 80 502 and 504 lock through the inner right contact of relay 504, conductors 518, 519 and 520 to ground at the middle right contact of relay 310. Relay 502 closes an obvious circuit for relay 507 which operates and locks 85 through its inner left contact to the grounded conductor 518. Relay 507 opens the shunt around relay 309 and this latter relay energizes in series with relay 508. Relay 309 opens the holding circuit of relay 90 307, which in turn, releases and opens the circuit of relays 309 and 508. Relay 508 disconnects the counting relays from the register 500 and relay 309 again closes the circuit of slow relay 308. It will be noted 95 that when relay 309 operates in series with relay 508 it opens the holding circuit of the counting relay 313.

100 The subscriber next operates his dial, and transmits the second series consisting of five impulses. In the manner already explained the first four impulses cause the successive operation of counting relays 312, 313, 314 and 315 and the successive deenergization of relays 312, 313 and 314. When the line is 105 opened for the fifth impulse, the circuit over conductor 322 is extended by way of the outer right front contact of relay 315, outer right back contact of relay 316, winding of relay 316 to ground over conductor 323. 110 Relay 316 operates, opens the holding circuit of relay 315 and locks in a circuit from battery through its inner right contact and winding to the grounded conductor 323. After an interval has elapsed following the 115 last impulse, relay 308 releases and the above traced circuit is extended from ground by way of conductor 324, right front contact of relay 507, right back contact of relay 511, winding of relay 512 to battery. Relay 512 operates, connects the counting relays to the register 501 and closes a circuit through its winding and contact, over conductor 517, thence as traced through the winding of relay 309 to ground. Relay 309 120 being shunted does not operate.

125 With relay 512 operated a circuit may be traced from ground over conductor 323, inner left contact of relay 316, inner left contact of relay 312, conductor 326, contact 130

of relay 512, winding of relay 509 to battery. Relay 509 operates and locks through its inner left contact, conductor 521 to the grounded conductor 519. Relay 509 at its 5 outer left contact closes an obvious circuit for relay 511 which operates and locks through its inner left contact to the grounded conductor 521. Relay 511 removes the shunt and permits the relay 309 10 to operate in series with relay 512. In the manner above described relay 309 causes the release of relay 307 which, in turn, causes the release of relays 309 and 512. Relay 308 again operates.

15 The subscriber manipulates his transmitter to send a third series consisting of three impulses. In response to this series relays 312, 313 and 314 are operated and relays 312 and 313 are successively released.

20 After an interval following the series of impulses relay 308 releases and the circuit over conductor 324 now leads through the right front contacts of relays 507 and 511, right back contact of relay 605, winding of 25 relay 604 to battery. Relay 604 operates and connects the counting relays to the register 600 and closes a holding circuit for itself over conductor 517 and the winding of relay 309 to ground. The relay 309 being 30 shunted does not operate.

With relay 604 operated circuits are completed from the grounded conductor 323, left front contacts of relay 314, conductors 327 and 325, respectively, contacts of relay 35 604, windings of relays 602 and 613 to battery. Relays 602 and 613 operate and lock through their inner right contacts, conductors 614 and 519 to ground. Relays 602 and 613 at the outer right contacts close an obvious circuit for relay 605. Relay 605 40 operates and locks through its inner left contact to the grounded conductor 614. Relay 605 removes the shunt and permits relay 309 to operate in series with relay 604. Relay 309 opens the circuit of relay 307 which 45 releases and, in turn, opens the circuit of relays 309 and 604. Relay 604 disconnects the counting relays from the register 600.

50 Lastly, the subscriber transmits the final series consisting of a single impulse and the counting relay 312 is operated. After an interval following the impulse, relay 308 releases and the circuit previously traced by way of conductor 324 now leads from the right front contacts of relays 507, 511 and 55 605, right contact of relay 607, winding of relay 606 to battery. Relay 606 operates, connects the counting relays to the register 601, closes a circuit through its winding 60 and inner upper contact by way of conductor 517, through the winding of relay 309 to ground. Relay 309, however, remains deenergized. With relay 606 operated a circuit is closed by way of grounded conductor 323, outer left front contact of relay 65

312, conductor 327, outer right front contact of relay 317, conductor 327, through the contact of relay 606, winding of relay 603 to battery. Relay 603 operates and locks through its inner right contact to the 70 grounded conductor 520. Relay 603 closes an obvious circuit for relay 607 which, in turn, operates and locks through its inner left contact and grounded conductor 520. Relay 607 removes the shunt and permits 75 relay 309 to operate in series with relay 606. Relay 309 unlocks the energized counting relay and also opens the circuit of relay 307. Relay 307, in turn, opens the holding circuit of relays 309 and 606. Relay 606 disconnects the counting relays from the register 80 601.

After the subscriber has set up the record on the sender, the district selector switch 200 is operated to seize an idle trunk 207 outgoing to the distant called office. During the operation of the switch 200, relay 206 is operated and locks through its inner upper contact, conductor 210, upper contact of relay 203 to the grounded conductor 111. Following the operation of relay 206, relay 205 is operated by the switch 200 in a suitable manner and locks through its left-hand armature to the conductor 210. After the connection has been extended to the distant office the apparatus is placed in condition to transmit code impulses over the trunk in accordance with the settings of the numerical registers in 90 Figs. 5 and 6 to operate the call indicator in the distant office. When the apparatus is ready for this purpose a circuit is completed in any suitable manner for the relay of 418. The manner in which the above mentioned operations take place is shown and described in detail in the above mentioned patent of 95 S. B. Williams.

100 Relay 418 closes a circuit from battery through the winding of relay 400, contact of relay 418, conductor 419, middle left contact of relay 607 to ground. Relay 400 105 operates and locks through its left contact, conductor 420 to ground at the inner right contact of relay 310. Relay 400 connects 110 the relay 404 to the tip and ring conductors of the line, resulting in a circuit as follows: battery through the middle lower contact of relay 708 in Fig. 7, conductor 723, right winding of relay 710, winding of relay 702, 115 inner normal contact of relay 704, outer contact of relay 700, thence over the tip side of the line through the switch 200 to the tip conductor of trunk 103, uppermost front contact of relay 206, inner right contact of 120 relay 205, conductor 211, through the selector switch 110, conductor 330, inner right contact of relay 400, outer right contact of relay 403, winding of relay 404, inner right contact of relay 403, outer right contact of relay 400, conductor 331, con- 125 130

ductor 212, outer right contact of relay 205, lower front contact of relay 206, thence over the ring side of the line, through the inner back contact of relay 700, outer normal 5 contact of relay 704, left winding of relay 710 to ground. Relay 710 operates and closes a circuit for relay 711. Relay 711 operates and at its outer left contact closes a circuit around the relay 702 preventing 10 this relay from operating in series with the right winding of relay 710. Relay 711 also closes a circuit from battery through the assignment lamp 713, lower winding of relay 712, outer right back contact of relay 15 715, inner upper contact of relay 712, inner right contact of relay 711 to ground. The lamp 713 illuminates to advise the operator that a call is awaiting attention on the incoming trunk 207. Due to the 20 character of relay 712, however, it is not energized through its lower winding sufficiently to attract its armatures.

The code impulses are sent to the receiving office over a full metallic circuit comprising both the tip and ring conductors of the line in series. These impulses may be of either positive or negative polarity dependent upon the pole of battery that is connected to a given side of the line circuit. They may also be weak or strong dependent upon whether a high or a low resistance is included in the circuit. The impulses are received by the relays 800, 801 and 802. The relay 800 is polarized in such 30 a manner as to respond only when current of positive polarity flows over the ring side of the line; that is, over the conductor 825. Relay 801 is polarized in such a manner as to respond to current of the opposite 35 polarity. Both relays 800 and 801 respond either to strong or weak impulses provided the polarity is in the proper direction. Relay 802 responds to strong impulses of either polarity but does not respond to weak impulses.

At the time the above traced impulse circuit is closed, relay 404 in the mechanical office also operates and closes a circuit from battery, through the winding of relay 405, 40 front contact of relay 404 to ground over conductor 420. Relay 405 operates and locks through its left contact to the conductor 420. A circuit is now closed from ground through the outer right contact 45 of relay 405, conductor 421, thence through the outer left contact of relay 507 and the outer left contact of relay 513 and in parallel through the corresponding contacts of relays 511, 515, 605, 608, over conductor 615, winding of relay 411 to battery. Relay 411 completes a circuit from ground through the outer right contact of relay 405, conductor 421, outer right contact of relay 411, inner right back contact of relay 414, inner right 60 contact of relay 412, outer right contact of

relay 413, left back contact of relay 414, left-hand windings of relays 415 and 414 to battery. Relay 415 operates in this circuit but relay 414 being marginal does not receive sufficient current to energize. Relay 415 closes a circuit from battery through the left-hand windings of relays 414 and 415, right-hand winding of relay 414, inner right contact of relay 415, conductor 421 to ground over conductor 420. Relay 414, however, does not operate since its right-hand winding is shunted by the circuit above traced. Relay 415 completes a circuit from ground through its outer right contact, contact of relay 416, conductor 423, outer right back contact of relay 513, winding of relay 514 to battery. Relay 514 operates and associates the impulse generating apparatus in Fig. 4 with the first register 500 to determine the character of the impulses of the first digit to be transmitted to the distant office. Relay 514 also closes a circuit from battery through its winding and inner lower contact, conductor 523, winding of relay 416 to ground at the outer 90 right contact of relay 415. Relay 416 being shunted by the previous circuit does not operate.

Returning to the called office, the operator observing the illumination of lamp 713 presses the individual assignment key 716 to associate the call indicator with the trunk 207. Key 716 closes a circuit from battery through the winding of relay 821, lower contact of relay 712, right winding of relay 715, upper contact of said key, contact of relay 816 to ground at the right back contact of relay 819. Relay 715 operates and locks in a circuit from battery through the winding of relay 821, lower contact of relay 712, windings of relay 715 to ground at its left contact. Relay 715 opens the original circuit of lamp 713 and connects this lamp in series with the interrupter 721. The lamp flashes during the period that impulses are being received and until the operator later inserts the plug of the cord circuit in the jack of a called line. Relay 715 also closes a circuit from battery through the winding of relay 700 and in parallel through the winding of relay 701, inner right contact of relay 715, winding of relay 816, left back contact of relay 819 to ground. Relay 700 operates and extends the tip and ring conductors of the 115 incoming trunk to the conductors 824 and 825, respectively.

When relay 700 operates it opens the circuit including relays 710 and 404. Relay 710 releases and opens the circuit of relay 711 which also deenergizes. Relay 404, in releasing, completes a circuit from battery through the winding of relay 403, inner right contact of relay 405, back contact of relay 404 to the grounded conductor 420. 130

Relay 403 operates and locks to the conductor 420.

Relays 407 and 408 at the mechanical office cooperate with each other to measure 5 intervals of time during which code impulses are produced and propagated over the line circuit to the distant office. Due to the characteristics of these relays they operate and release slowly. Relays 412, 413, 10 414 and 415 operate in a definite sequence and their function is to measure a sufficient number of periods of code impulses to represent each of the different digits. The mechanism is so arranged that all digits are 15 sent out without interruption or delay between digits.

With relay 403 energized a circuit is closed from battery through the resistance 409, winding of relay 407, left back contact 20 of relay 408, conductor 425, outer left contact of relay 411, conductor 426 to ground at the outer left contact of relay 403. Relay 407 energizes after an interval and closes a circuit from battery through the resistance 410, winding of relay 408, inner left contact of relay 407 to the grounded conductor 425. Relay 408 operates after an interval and closes a circuit from battery through the winding of relay 406, normal contact of said relay, outer right front contact of relay 408 to the grounded conductor 425. Relay 406 operates and locks 25 through its inner left front contact to the grounded conductor 425. Relay 408, in operating closes a circuit from battery through the resistance 409, middle right contact of relay 408 to the grounded conductor 425. This circuit shunts the relay 407 which commences to release. After an 30 interval relay 407 becomes deenergized and a circuit is closed from battery through the resistance 410, right back contact of relay 407 to the grounded conductor 425. This circuit shunts the relay 408 which, after an interval, releases its armatures.

The interval measured by the release of relays 407 and 408 is used for sending the first impulse of the code representing the digit in case any impulse is to be sent. In 50 the present instance, since the register relay 503 is not operated, no impulse is sent during this period. When relay 408 releases a circuit is closed from battery through the resistance 402, winding of relay 401, outer left contact of relay 407, inner right contact of relay 408, inner right contact of relay 406 to the grounded conductor 425. Relay 401 operates and locks 55 through its right contact to the grounded conductor 425.

Relay 408 also closes a circuit from the grounded conductor 425 through the outer right back contact of said relay, outer left contact of relay 406, conductor 427, left back 60 contact of relay 412, left-hand winding of

relay 413, left-hand winding of relay 412 to battery. Relay 413 operates but relay 412 being marginal does not energize sufficiently to attract its armatures. Relay 413 closes a circuit from battery through the left winding of relay 412, left winding of relay 413, right winding of relay 412, inner right contact of relay 413 to the grounded conductor 420. Relay 412, however, does not operate since its right winding is shunted by the above traced circuit. Relay 413, in operating, removes the shunt from the right winding of relay 414 and this latter relay attracts its armatures. Relay 414 closes a circuit from battery through the winding of relay 513, lower contact of relay 514, conductor 525, outer right contact of relay 414 to the grounded conductor 420. Relay 513 operates, locks through its inner right contact to the grounded conductor 519 and removes the shunt from the relay 416. Relay 416 operates in series with relay 514.

Relay 408, in releasing, recloses the operating circuit of relay 407, which after an interval, attracts its armatures and, in turn, closes the operating circuit of relay 408. Relay 408 operates after an interval of time. While relays 407 and 408 are undergoing energization a circuit is closed as follows for transmitting a code impulse over the line: from ground, which represents the positive pole of battery through the outer right contact of relay 406, conductor 428, inner left contact of relay 411, conductor 429, inner left front contact of relay 401, inner right contact of relay 409, conductor 330, thence through the selector switch 110, conductor 211, inner right contact of relay 205, upper front contact of relay 206, thence over the tip side of the line, through the outer front contact of relay 700, conductor 824, through the windings of relays 800, 801 and 802, conductor 825, inner front contact of relay 700, thence over the ring side of the line, through the lower front contact of relay 206, outer right contact of relay 205, conductor 212, through the selector switch 110, conductor 331, outer right contact of relay 400, middle left front contact of relay 401, outer left contact of relay 401, conductor 430, outer right back contact of relay 412, conductor 431, contact of relay 514, inner left contact of relay 504, low resistance 527 to the negative pole of battery. Due to the low resistance 527 a heavy impulse is transmitted of such a polarity as to cause the operation of relay 801. The impulse being heavy the marginal relay 802 is also operated. A circuit may now be traced from battery through the left windings of

relays 803 and 804, left back contact of relay 803, conductor 827 and contact of relay 801, conductor 828, left contact of relay 821, outer left contact of relay 822 to ground. Relay 804 operates but relay 803 being

— marginal remains inert. Relay 804 completes a circuit from battery through the left-hand windings of relay 803 and 804, right winding of relay 803, inner right contact of relay 804, conductor 829 to the grounded conductor 828. Relay 803, however, does not operate since its right winding is shunted by the circuit above traced. Relay 804 closes a circuit from ground over conductor 829, outer right contact of said relay, left back contact of relay 807, winding of relay 808 to battery. Relay 808 operates and closes a circuit from battery through its winding and the winding of relay 807, inner right contact of relay 808 to the grounded conductor 829. Relay 807, however, being shunted does not operate at this time. Another circuit is closed from the grounded conductor 828, contact of relay 802 outer right back contact of relay 803, inner right back contact of relay 807, conductor 831, left winding of register relay 900 to battery. Relay 900 locks in a circuit through its windings and inner right contact, conductors 901 and 902, right contact of relay 821 to ground at the right contact of relay 822.

When relay 408 operates, as above explained, it closes a circuit from battery through the resistance 402, conductor 433, middle left contact of relay 406, outer right front contact of relay 408 to the grounded conductor 425. This circuit shunts the relay 401, which thereupon releases its armatures. Relay 401 at its left contacts opens the impulse circuit and terminates the impulse being transmitted over the line. Relays 801 and 802 thereupon release. Relay 801 removes ground from conductor 827 whereby the relay 803 operates in series with relay 804. Relay 803, in operating, opens the above traced shunt around the winding of relay 807. However, this shunt is maintained at the outer right contact of relay 804. Relay 408, in operating, also removes ground from the conductor 427 whereby relay 412 operates in series with relay 413.

Next the relays 407 and 408 are deenergized in succession in the manner above explained and during the deenergization measure a period for the transmission of an impulse over the line in case the register 500 is properly positioned for this purpose. In the present case, however, since the relay 505 is not operated, no impulse is transmitted to the distant office. Following the deenergization of relay 408 a circuit is closed from the grounded conductor 425, outer right back contact of relay 408, left contact of relay 406, conductor 427, left front contact of relay 412, left-hand winding of said relay to battery. This circuit shunts the relay 413 which thereupon releases. Relay 408, in releasing, also opens the shunt around re-

lay 401 which attracts its armatures and terminates the impulse period.

Next the relays 407 and 408 are operated in succession and during this interval a circuit is closed from the positive pole of battery over conductor 428, inner left contact of relay 411, conductor 429, inner left front contact of relay 401, inner right contact of relay 400, thence over the tip side of the line through the windings of relay 800, 801 and 802 and returning over the ring side of the line through the outer right contact of relay 400, middle front contact of relay 401, conductor 434, high resistance 528 to the negative pole of battery. Due to the high resistance 528 relay 802 remains de-energized and due to the polarity of the impulse, relay 801 operates. Relay 801 applies ground potential to the conductor 827 whereby relay 804 is shunted and releases while relay 803 remains locked through its left-hand winding. Relay 804 removes the shunt from the relay 807 which still remains shunted due to relay 803. When relay 408 becomes energized it recloses the shunt around relay 401 and this latter relay releases, and opens the impulse circuit causing the release of relay 801. Relay 801 opens the holding circuit of relay 803 which becomes deenergized. With relay 803 released relay 807 operates in series with relay 808. Relay 408 also removes ground from conductor 427 whereby relay 412 releases. Relay 412 completes a circuit from battery through the left-hand winding and left front contact of relay 414, outer right contact of relay 413, inner right contact of relay 412, inner right front contact of relay 414, inner right contact of relay 415 to ground over conductor 421. This circuit shunts the relay 415 which releases its armatures. Relay 415, in releasing, opens the holding circuit of relay 414 which also de-energizes. Relay 415 at its outer right contact opens the holding circuit of relays 514 and 416. Relay 514 disconnects the impulse mechanism from the register 500.

The circuit above traced for relays 414 and 415 is again completed and relay 415 operates while relay 414 being marginal remains deenergized. The apparatus is now in condition to transmit the second digit to the distant office. Relays 407 and 408 next undergo deenergization in succession. When relay 408 becomes deenergized it opens the shunt around relay 401 and this relay operates. Relay 408 also closes the above traced circuit for relays 412 and 413 and relay 413 operates while relay 412 remains deenergized. Relay 413, in operating, removes the shunt from relay 414 and this relay operates in series with relay 415.

At the time relay 415 operated it completed a circuit from ground through its outer right contact, contact of relay 416,

conductor 423, outer right front contact of relay 513, outer right back contact of relay 515, winding of relay 516 to battery. Relay 516 operates and closes a circuit through its 5 winding and contact, thence over conductor 523, through the winding of relay 416 to ground at the outer contact of relay 415.

When relay 414 operates a circuit is closed from battery through the winding of relay 10 515, lower contact of relay 516, conductor 525, outer right contact of relay 414 to the grounded conductor 421. Relay 515 operates and locks through its inner right contact of the conductor 521. Relay 515 also removes 15 the shunt from relay 416 and this latter relay operates in series with relay 516.

Next the relays 407 and 408 undergo operation during which period a circuit is closed from the positive pole of battery over 20 conductor 429, inner left front contact of relay 401, thence over the tip side of the line and returning over the ring side of the line through the middle front contact of relay 401, conductor 434, high resistance 25 528 to the negative pole of battery. This circuit results in a weak impulse of the proper polarity to operate the polarized relay 801. Relay 801 applies ground potential to the conductor 827 and relay 804 operates 30 in the manner above described. Relay 804 closes a circuit from ground over conductor 829, through the outer right contact of said relay, left front contact of relay 807, left back contact of relay 809, winding of relay 35 810 to battery. Relay 810 operates and closes a locking circuit for itself in series with relay 809 to the grounded conductor 829. Relay 809, however, does not operate since it is shunted.

40 When relay 408 becomes energized it closes the shunt for relay 401 and this latter relay releases to in turn cause the release of relay 801. Relay 801 removes the shunt from relay 803 and this latter relay operates 45 in series with relay 804. Relay 408 in operating also removes ground potential from conductor 427 whereby relay 412 operates in series with relay 413.

The relays 407 and 408 now become de- 50 energized in succession following which, relay 401 operates and relay 413 releases in the manner described.

Next relays 407 and 408 operate in succession and during the interval required for 55 them to attract their armatures a circuit is established from the positive pole of battery over conductor 429, inner left front contact of relay 401, thence over the tip side of the line and returning over the ring 60 side of the line, through the middle and outer left front contacts of relay 401, conductor 430, outer right front contact of relay 412, conductor 332, upper contact of relay 516, right contact of relay 509, low resistance 527 to the negative pole of

battery. This circuit results in a heavy impulse causing the operation of relay 802 and also of the polarity to energize relay 801. Relay 801 shunts relay 804 which releases and removes the shunt from relay 809. Relay 809, however, remains operated since the shunt is maintained by relay 803. Another circuit is closed from the grounded conductor 829, through the contact of relay 802, outer right front contact of relay 803, outer right front contact of relay 807, outer right back contact of relay 809, conductor 834, left winding of relay 903 to battery. Relay 903 locks through its windings and inner left front contact to the grounded conductor 901. After relays 407 and 408 have operated relays 412, 415, 414 and 401 become deenergized in the manner hereinbefore described. Relay 415, in releasing, 70 opens the holding circuit of relays 516 and 416 and these relays deenergize. Relay 415 now becomes operated in the manner previously described. Relay 415 closes the above traced circuit from ground through its outer right contact, contact of relay 416, over conductor 423, outer right front contacts of relays 513 and 515, outer right back contact of relay 608, winding of relay 809 to battery. Relay 809 operates and 75 closes a circuit from battery through its winding and inner lower contact, thence over the conductor 523, winding of relay 416 to ground. Relay 416 being shunted does not operate. The apparatus is now in condition 80 to transmit the third or tens digit.

Next, the relays 407 and 408 undergo de- 85 energization, during which period, a circuit is closed from the positive pole of battery over conductor 429, middle normal contact of relay 401, thence over the ring side of the line and returning over the tip side of the line through the inner left normal contact of relay 401, conductor 436, left back contact of relay 413, inner right contact of relay 411, conductor 438, inner left front contacts of relays 513 and 515, inner left back contact of relay 608, left contact of relay 602, high resistance 528 to battery.

It will be observed that the impulse circuit above traced through contacts of the first relay 602 of register 600 leads through a contact of relay 608 and does not pass through contacts of relay 609. This is to permit the first pulse to be sent immediately and is also true of the other registers. The impulse transmitted in this circuit is weak due to the high resistance 528 and of such polarity as to operate the relay 800. Relay 800 closes a circuit from ground over conductor 828, left back contact of relay 804, left front contacts of relay 808 and 810, left back contact of relay 812, conductor 835, left winding of relay 904 to battery. Relay 904 operates and locks through its windings to the grounded conductor 902.

After relay 408 has become energized relays 413, 414 and 401 operate. Relay 401 interrupts the impulse being transmitted and relay 800 becomes deenergized.

- 5 Next the relays 407 and 408 become operated. During this period a circuit is closed from the positive pole of battery, over conductor 429, inner left front contact of relay 401, thence over the tip side of the line and returning over the ring side of the line through the middle and outer left front contact of relay 401, conductor 430, outer right back contact of relay 412, conductor 431, contact of relay 609, left contact of relay 613, 70 low resistance 527 to the negative pole of battery. A heavy impulse is transmitted in this circuit whereby relays 801 and 802 are operated. Relay 801 causes the operation of relay 804 whereupon a circuit is closed from ground over conductor 829, through the outer right contact of relay 804, left front contacts of relay 807 and 809, left back contact of relay 811, winding of relay 812 to battery. Relay 812 operates and prepares 75 a circuit for relay 811, but this latter relay being shunted does not attract its armatures. Another circuit is closed from the grounded conductor 829, through the contact of relay 802, outer right back contact of relay 803, inner right front contacts of relays 807 and 809, inner right back contact of relay 811, conductor 836, contact of relay 905 to battery. Relay 905 operates and locks 80 through its winding to the grounded conductor 902.

After relay 408 operates relay 412 energizes and relay 401 becomes deenergized. Relay 401 interrupts the impulse circuit and relays 801 and 802 become deenergized.

- 40 Relay 801 permits relay 803 to operate in series with relay 804.

Next the relays 407 and 408 become deenergized at the end of which period, relay 415 releases and relay 401 operates.

- 45 Next relays 407 and 408 become energized and during this period a circuit is closed from the positive pole of battery, over conductor 429, inner left front contact of relay 401, thence over the tip side of the line and returning over the ring side of the line through the middle front contact of relay 401, conductor 434, high resistance 528 to battery. Due to the character of this impulse, relay 801 alone is operated. Relay 50 801 closes a shunt for relay 804 and this relay becomes deenergized. After relay 408 has operated, relays 412, 415, 414 and 401 become deenergized. Relay 401 opens the impulse circuit and causes the release of relay 801. Relay 801 opens the circuit of relay 803, which in turn, permits relay 811 to operate in series with relay 812.

55 Relay 415 immediately operates as above described and closes a circuit over conductor 423 through the outer right front contacts

of relays 513, 515 and 608, outer right back contact of relay 610, winding of relay 611 to battery. Relay 611 operates and closes a circuit through its winding and inner lower contact, conductor 523, winding of relay 416 70 to ground. Relay 416 being shunted does not operate. The equipment is now in condition to transmit the last digit.

Relays 407 and 408 undergo deenergization during which time a circuit is closed from the positive pole of battery over conductor 429, middle normal contact of relay 401, thence over the ring side of the line and returning over the tip side of the line through the inner left normal contact of relay 401, conductor 436, left back contact of relay 413, inner right contact of relay 411, conductor 438, inner left front contacts of relays 513, 515 and 608, left contact of relay 610, left contact of relay 603, high resistance 85 528 to the negative pole of battery. Due to this impulse relay 800 operates and a circuit is closed from ground over conductor 828, left back contact of relay 804, left front contacts of relays 808, 810 and 812, conductor 838, winding of relay 906 to battery. Relay 906 operates and locks to the grounded conductor 902. When relay 408 releases relays 413, 414 and 401 become energized. Relay 401 opens the circuit of relay 800. 90

Next the relays 407 and 408 become energized during which period a circuit is closed from the positive pole of battery over conductor 429, through the inner left front contact of relay 401, over the tip side of the line, returning over the ring side of the line, through the middle left front contact of relay 401, conductor 434, high resistance 528 to the negative pole of battery. This impulse causes relay 801 to operate whereby relay 804 becomes energized. Relay 804 closes a circuit from grounded conductor 829, outer right contact of relay 804, left front contacts of relays 807, 809 and 811, inner left back contact of relay 813, winding of relay 814 to battery. Relay 814 operates and closes a circuit for itself in series with relay 830, but this latter relay remains deenergized since it is shunted. At the end of a period when relay 408 operates relay 412 becomes energized and relay 401 releases. Relay 401 opens the circuit of relay 801 and relay 803 becomes energized. 105 110 115

Next the relays 407 and 408 become deenergized, at the end of which interval, relay 413 releases and relay 408 operates.

Lastly, relays 407 and 408 operate. During this period, a circuit is closed from the positive pole of battery over conductor 429, inner left front contact of relay 401, over the tip side of the line and returning over the ring side of the line through the middle left front contact of relay 401, conductor 434, high resistance 528 to battery. Due to the impulse in this circuit relay 801 operates. 120 125 130

ates and relay 804 becomes deenergized. After relay 408 becomes energized relays 412, 413, 415 and 401 become deenergized. Relay 401 opens the impulse circuit and relay 801 becomes deenergized to, in turn, cause the release of relay 803. Relay 803 opens the shunt around relay 813 and this relay operates in series with relay 814.

Before proceeding with the operations at 10 the distant office involving the illumination of the operator's call indicator, an explanation will be given of the release of the register sender in the mechanical office. When relay 415 releases it opens the circuit of relay 416 and the circuit of relay 611. Following this, the relay 415 is again operated in the manner above explained and a circuit is established from ground through the outer right contact of relay 415, contact of relay 416, conductor 423, outer right front contacts of relays 413, 415, 608 and 610, lower back contact of relay 611, conductor 617, winding of release relay 311 to battery. Relay 311 operates and locks to the 20 grounded conductor 320. Relay 311 at its left contacts opens the holding circuit of relay 300, which in turn, opens the circuit of relay 304. After an interval relay 304 releases and opens the circuit of relay 310. Relay 310 removes ground from conductors 321, 320, 420 and 520, whereupon the sender selector switch 110 and all energized relays in the sender and register are restored to 30 normal. Thus the register sender is disassociated and may be taken for use in connection with other calls.

When the sender is released and ground potential is removed from conductor 320, relay 203 becomes deenergized. Relay 203 releases and extends the tip and ring conductors of the trunk 103 through to the left-hand windings of the repeating coil 201. Relay 202 is now operated in series with the calling line and closes a substitute holding circuit for the slow relay 204. In this manner the release of the connection is placed under the control of the subscriber's switch-hook. Relay 203, in releasing also opens the holding circuits of relays 205 and 206. Relay 206 releases and extends the tip and ring conductors of the trunk 103 through to the right-hand windings of repeating coil 201.

Returning to the call indicator apparatus in the distant office, at the time relay 813 operates, a circuit is closed from ground through the outer left contact of said relay, contact of relay 818, winding of relay 819 to battery. Relay 819 operates and opens the circuit of relays 700 and 701. Relay 700 extends the tip and ring conductors of the trunk 207 through to the left-hand windings of repeating coil 720, whereupon the following circuit is completed: battery, through the middle lower contact of relay 708, con-

ductor 723, right-hand winding of relay 710, winding of relay 702, inner normal contact of relay 704, thence over the tip side of the line through the upper right-hand winding of repeating coil 201, winding of polarized relay 214, lower right-hand winding of coil 201 and returning over the ring side of the line through the outer normal contacts of relay 704, left hand winding of relay 710 to ground.

At the time relay 812 operates it closes an obvious circuit for relay 815. When the relay 813 is subsequently energized circuits are completed for energizing the numerical lamps in accordance with the digits recorded on the register relays in Fig. 9. Since the numerical designation is 2 5 3 1 the No. 2 thousands lamp 910 is illuminated in a circuit from battery, through the lower right contact of relay 815, conductor 839, inner right back contact of relay 908, left front contact of relay 900, inner left back contact of relay 909, lamp 910, outer right front contact of relay 900, outer left contact of relay 909, outer right back contact of relay 911, conductor 912, lower left contact of relay 815 to the grounded conductor 829. Also a circuit is closed from battery through the upper right contact of relay 815, conductor 840, lamp 913, left back contact of relay 914, outer right back contact of relay 915, left back contact of relay 916, inner left front contact of relay 903 to ground over conductor 901. Moreover, another circuit is closed from battery through the outer right contact of relay 814, conductor 841, inner right back contact of relay 918, left front contact of relay 905, inner left front contact of relay 904, lamp 917, inner left back contact of relay 918 to the grounded conductor 902. Lastly, a circuit is closed from battery through the right front contact of relay 813, conductor 842, inner right back contact of relay 919, left back contact of relay 920, outer right front contact of relay 906, lamp 920, outer left contact of relay 919 to ground over conductor 902.

The operator reads the number from the lamps of the call indicator, seizes the plug 717 and inserts it in the jack 718 of the called line 115 719. A circuit is now closed from ground through the sleeve relay 725, sleeve of the jack 718, sleeve of plug 717, winding of relay 708, outer right contact of relay 711, which is operated at this time, contact of 120 relay 709, inner back contact of relay 706, winding of relay 707 to battery. A branch of this circuit extends through the winding of relay 706, but this relay being shunted does not operate. A parallel circuit is also closed through the disconnect lamp 714, but since lamp 714 is shunted it does not illuminate. Relay 708 operates and at its lowermost front contact closes a circuit for the upper winding of relay 712. Relay 712 125

operates and opens the circuit of relays 821 and 715. Relay 715 disconnects the interrupter 721 from the lamp 713 and this lamp is extinguished. Relay 821 removes ground from the conductors 828 and 902 causing the release of all relays and the extinguishment of all illuminated lamps in the call indicator mechanism.

Relay 707 operates in the circuit above traced and closes a circuit from the source of ringing current through the marginal relay 709, lower front contact of relay 707, ring of the plug and jack, thence over the subscriber's line and returning through the tip and the plug and jack, upper front contact of relay 708, upper contact of relay 707 to ground. When the subscriber responds to the ringing of his bell, the marginal relay 709 operates, removes the shunt and permits relay 706 to become energized. Relay 706 closes a circuit from battery through its inner front contact and winding and thence to ground through the sleeve relay 725 whereby relay 707 is shunted out and releases. Relay 707 completes the tip and ring conductors through to the right-hand windings of the repeating coil 720. Relay 705 operates in series with the called line and closes an obvious circuit for relay 704. Relay 704 serves to reverse the current over the line which may be used for any desired purpose.

After the conversation has finished, the calling subscriber by replacing his receiver on the switchhook opens the circuit of relay 202, which in turn, opens the circuit of relay 204. After an interval relay 204 releases and removes ground from conductor 111 whereby the line switch 100 and the district switch 200 become deenergized to restore the connection.

When the trunk at the mechanical office is released the circuit of relay 710 in the distant office is opened and the relay 711 consequently releases. Relay 711 at its outer right contact removes the shunt from around the lamp 714 and this lamp illuminates to advise the operator that the connection is no longer required. She, thereupon, withdraws the plug 717 from the jack 718 and all energized relays associated with the cord circuit are released.

It has thus been explained how the impulse generating equipment associated with the register sender in the mechanical office creates and transmits codes of impulses representing digits recorded on the registers to affect apparatus in the distant exchange. While only the four numerical digits characterizing the line number have been considered in this system it, of course, will be understood that the same mechanism may be employed for transmitting as many other digits as is necessary for the particular type of system concerned.

What is claimed is:

1. The combination in a telephone system of a designation recording mechanism, impulse responsive means for setting up a record on said mechanism, a second recording mechanism, and a device consisting of relays for originating and sending code impulses to transfer the record from said first mechanism to said second mechanism. 70

2. The combination in a telephone system 75 of a register controlling sender, means for setting up a designation record on said sender, a recording mechanism located at a distant point, a two-wire transmission circuit and a device comprising relays for originating and sending code impulses over said circuit to transfer the record from said sender to said distant recording mechanism.

3. The combination in a telephone system 80 of a register controlling mechanism, means for setting up records on said mechanism, selective switches for extending connections, said switches being controlled by said mechanism, a recording mechanism, and an impulse sending device comprising a plurality of relays for creating and transmitting code impulses to transfer records from said controlling mechanism to said recording mechanism, 90

4. In a telephone system, an office having 95 a designation recording mechanism, therein, means for setting up records on said mechanism, a distant office having a second recording mechanism therein, and a device comprising a number of cooperating relays 100 for originating and transmitting impulses to transfer a record from the recording mechanism in said first office to the recording mechanism in said second office.

5. In a telephone system, a designation 105 recording mechanism, means for setting up records on said mechanism, a second recording mechanism, a two-wire impulse circuit interconnecting said recording mechanism and a device consisting of relays for creating 110 and transmitting code impulses over said impulse circuit to transfer records from said first recording mechanism to said second recording mechanism.

6. In a telephone system, a designation 115 recording mechanism, means for setting up records on said mechanism, a second recording mechanism, and a pair of intercontrolling relays for measuring and sending code impulses to transfer records on said first recording mechanism to said second recording mechanism. 120

7. In a telephone system, an office having 125 switches and recording mechanism therein, a distant office having a second recording mechanism therein, means for operating said switches to extend a connection from the first to the second office, and a device consisting of relays for generating and sending code impulses over said connection to 130

transfer records from the recording device in the first office to the recording device in the second office.

8. In combination in a telephone system of a designation recording mechanism, means for setting up records on said mechanism, a second recording mechanism, a device comprising a number of relays for originating and sending impulses of different character

to transfer records from the first recording mechanism to the second recording mechanism, and an indicating device controlled in accordance with the records established on said second recording mechanism. ¹⁰

In witness whereof, I hereunto subscribe ¹⁵ my name this 18th day of May A. D. 1923.

EARL S. GIBSON.
